PIPE

John C. Shetton, Lakewood, Ohio

Application March 8, 1933, Serial No. 660,025

4 Claims. (Cl. 131—12)

This invention relates to pipes, and has for its general object to produce a pipe which can be cleaned in a most effective manner and which will be provided with means whereby the draft through the bore of the stem may be conveniently and readily controlled in accordance with the quality of the tobacco used in the pipe and the taste of the particular smoker. Further and more limited objects of the invention will be set forth at length in the specification and will be realized through the construction shown in the drawing, wherein Fig. 1 represents a central longitudinal sectional view through a pipe constructed in accordance with my invention; Fig. 2 a detail in central longitudinal section of the bowl and a portion of the stem of said pipe; Fig. 3 a detail in section corresponding to the line 3—3 of Fig. 2; Fig. 4 an elevation of the means for supplying cool air to the bore of the stem of said pipe; and Fig. 5 a central longitudinal sectional view of said pipe, showing the manner in which a cleaner may be employed therewith.

As is well known to smokers, there is a tendency for liquid to collect in the bottoms of the bowls of pipes, which liquid not only gives off nicotine, but also is liable to enter the bore of the stem, with consequent discomfort to the smoker. Furthermore, as is also well known, some smokers prefer to use a comparatively strong and moist tobacco with the production of what is known as a heavy smoke, while others prefer to use a relatively mild and dry tobacco, with the production of what is known as a light smoke. Still further, some smokers prefer a pipe and a grade of tobacco which will produce a relatively warm smoke, while others prefer to use a pipe and a grade of tobacco which will produce a relatively cool smoke. Furthermore, if tobacco be pressed fairly firmly into the bowl of an ordinary pipe, for the purpose of securing a prolonged smoke without refilling, there is danger of clogging the bore of the stem.

By the use of my invention as shown and described herein, I am enabled to overcome the objectionable features and to realize the desirable objects hereinbefore recited, and to accomplish these results by the use of a single pipe which is equipped with such invention.

Describing the various parts by reference characters, 1 denotes the bowl and 2 the stem of a pipe, the stem being provided with a bore consisting of a section 3, the said section merging adjacent to the bore with a section 3^a of slightly greater diameter. The outer side of the bowl (the side remote from the stem 2) is provided

with a bore section 3^b therethrough, which is preferably of the same diameter as the section 3^a. It will be noted that the bottoms of the bore sections 3^a and 3^b are substantially flush with the bottom of the bowl 1.

Mounted in the bore sections 3^a and 3^b and extending across the bottom of the chamber of the bowl of the pipe is a tube 4, which tube is preferably constructed of a metal capable of becoming heated quickly, such as aluminum. The internal diameter of the tube 4 is equal to the diameter of the bore section 3 whereby the interior of the tube constitutes a continuous extension of the bore section 3 across the bottom of the chamber of the bowl and through the wall thereof which is remote from the mouthpiece. This tube is provided with a narrow slot 4^a in the top thereof and with corresponding slots 4^b in opposite sides thereof and above the bottom of the tube and the bottom of the bowl. These slots are sufficiently narrow to prevent clogging of the draft through the bore 3 by packing tobacco in the bowl. The slots 4^b are located above the bottom of the bowl to prevent or limit access thereto of any moisture that may tend to accumulate in the bottom of the bowl, although such accumulation is reduced to a minimum by the heat received and dissipated by the tube 4. The aggregate areas of the slots 4^a and 4^b will be sufficient to satisfy one desiring a "heavy smoke". However, in order to accommodate the pipe for the use of those desiring varying degrees of a lighter smoke, there is fitted within the tube 4 a tubular damper 5 having slots 5^a and 5^b preferably of the same width and length as the slots 4^a and 4^b, respectively, and adapted to register more or less therewith, accordingly as the tube 5 is rotated by means of the integral head 6 which is formed therewith and which abuts against the side of the bowl which is remote from the stem and closes the outer end of the bore 3^b and prevents access of outside air to the end of the tube 4 which is mounted in said bore. The head 6 is preferably circular in outline and is shown as formed integral with the tube 5.

In order to enable the smoker to vary the warmth of the smoke, I have provided the head 6 with a plurality of openings 6^a therethrough and have mounted on the said head, by means of a central stud or rivet 7, a rotary damper 8 having openings 8^a therein and adapted to be brought more or less into register with the openings 6^a. By rotating this damper more or less, air may be admitted through the openings 8^a with corresponding cooling of the smoke and neutralization 55 6

or dilution of the carbon monoxide contained therein.

Due to the construction and arrangement of the parts as thus far described, I am enabled to produce a pipe which will accommodate the tastes of all classes of smokers, so far as the quality and temperature of the smoke is concerned; also to neutralize or dilute more or less the carbon monoxide content of the smoke as well as to vary the temperature of the smoke; also to prevent the bore of the stem from becoming clogged by packing tobacco in the bowl as when it is desired to have a prolonged smoke with one filling.

There is another important result which may be accomplished by my invention which will be apparent more particularly from Fig. 1. Should any liquid enter the tube 4 and the bore 3, this liquid may be effectively removed without leaving any residual part of such liquid in the portion of the bore which is adjacent to the mouthpiece. Furthermore, I am enabled to accomplish this result with the utilization of the entire length of the cleaning element which is usually employed for pipes. One of these elements is indicated at 9, and is preferably of the usual type of cleaning brush, consisting of central wires 9^a having entwined therewith fibrous absorbent material 9^b. By removing the tube 5, this brush can be inserted into the mouthpiece end of the stem and, being longer than the bore 3, can be pushed and pulled entirely through said bore and the tube 5.

It will be noted that, due to my construction, the bore, comprising the tube 4, and the slots therein are subjected to the cleaning action of the entire length of the brush and that, because it is not necessary to reciprocate the brush, none of the liquid material that may adhere thereto need be carried thereby into the portion of the bore at or adjacent to the mouthpiece. The tube 5 may be cleaned when removed, either by a brush or by any other convenient cleaning means. Furthermore, there is no necessity for using a two-part stem (although such a stem is shown herein), as there will be no occasion for removing an outer stem section for cleaning purposes.

It will be evident that the tube 4 constitutes a part of the bore, whereby the said bore extends throughout the length of the stem and entirely across the bowl and through the wall thereof which is remote from the mouthpiece; that, by providing this extended bore with a removable closure, the bore may be cleaned most effectively and without bringing any of the moisture which may be therein to or adjacent to the mouthpiece. Also that no trap is provided between the bowl and the mouthpiece for the accumulation of any liquid. In addition, because of the other features of construction which have been described herein, I am enabled to accommodate a pipe equipped with my invention to various grades of tobacco and to varying tastes of smokers.

Having thus described my invention, what I claim is:

1. A pipe comprising a bowl and a stem, the said pipe being provided with a bore section extending through the said stem from the outer end thereof to a point adjacent to the bottom of the bowl and having a second bore section of slightly greater diameter than the first bore section and a third bore section of substantially the same diameter as the second bore section and extending through the wall of the bowl opposite said stem, the upper portions of the second and third bore sections intersecting the opposite sides of the bowl, above the bottom thereof, a metallic

tube mounted in the second and third bore sections and projecting above the bottom of the cavity of the bowl and provided with one or more openings in the upper portion thereof communicating with the cavity of said bowl, the said tube having an internal diameter substantially the same as the diameter of the first bore section, thereby to permit a cleaner to be projected entirely through the said bore section and tube, a removable closure for the outer end of said tube, a second tube rotatably and removably mounted with respect to the first mentioned tube and having one or more openings adapted to be brought into registry with the opening or openings in the first mentioned tube, said second tube having a head of a diameter greater than the first tube, abutting the outer end of the first tube and formed of the second tube material, said heads being perforated and a damper rotatably secured to the head and having openings therein adapted to register with the openings in the head.

2. A pipe comprising a bowl and a stem, the said pipe being provided with a bore section extending through the said stem from the outer end thereof to a point adjacent to the bottom of the bowl and having a second bore section of slightly greater diameter than the first bore section and a third bore section of substantially the same diameter as the second bore section and extending through the wall of the bowl opposite said stem, the upper portions of the second and third bore sections intersecting the opposite sides of the bowl, above the bottom thereof, and a metallic tube mounted in the second and third bore sections and projecting above the bottom of the cavity of the bowl and provided with a passageway consisting of a plurality of openings all of which are above the bottom of the cavity of said bowl, the said tube having an internal diameter substantially the same as the diameter of the first bore section, thereby to permit a cleaner to be projected entirely through the said bore section and tube, and a second tube rotatably and removably mounted with respect to the first mentioned tube and having a passageway consisting of a plurality of openings adapted to be brought into registry with the corresponding openings in the first mentioned tube and having means for closing the outer end of the first mentioned tube.

3. A pipe comprising a bowl and a stem, the said pipe being provided with a bore section extending through the said stem from the outer end thereof to a point adjacent to the bottom of the bowl and having a second bore section of slightly greater diameter than the first bore section and a third bore section of substantially the same diameter as the second bore section and extending through the wall of the bowl opposite said stem, the upper portions of the second and third bore sections intersecting the opposite sides of the bowl, above the bottom thereof, and a metallic tube mounted in the second and third bore sections and provided with lateral and vertical passageways located above the bottom of the bowl and communicating with said bowl, the said tube having an internal diameter substantially the same as the diameter of the first bore section, a second tube rotatably and removably mounted with respect to the first mentioned tube and having lateral and vertical passageways adapted to be brought into registry with the corresponding passageways in the first mentioned tube and having means for closing the outer end of the first mentioned tube, said means being provided with one or more openings for admitting air

therethrough into the tube, and a damper cooperating with such closing means to control the area or areas of the opening or openings therethrough.

- 5 4. A pipe comprising a bowl and a stem, the said pipe being provided with a bore section extending through the said stem from the outer end thereof to a point adjacent to the bottom of the bowl and having a second bore section of slightly 10 greater diameter than the first bore section and a third bore section of substantially the same diameter as the second bore section and extending through the wall of the bowl opposite said stem, the upper portions of the second and third bore 15 sections intersecting the opposite sides of the bowl, above the bottom thereof, a metallic tube

mounted in the second and third bore sections and projecting above the bottom of the cavity of the bowl and provided with one or more elongated slots in the upper portion only thereof communicating with the cavity of said bowl, the said tube having an internal diameter substantially the same as the diameter of the first bore section, thereby to permit a cleaner to be projected entirely through the said bore section and tube and into and longitudinally of said slot or slots, whereby a bristled cleaner when projected through the bore and tube will clean the bore, the tube, and the slot or slots thereof, and a removable closure for the outer end of said tube.
